UNITED STATES PATENT OFFICE.

EDGAR H. WEIL, OF CLEVELAND, OHIO.

PROCESS OF ENAMELING.

Application filed January 18, 1926. Serial No. 82,053.

This invention relates to an improved process of vitreous enameling table tops and similar articles having broad faces.

The invention is adapted for use in vitreous enameling trays, splashes, broiler pans, roofing tiles and similar articles having relatively large, broad faces; thus "table tops and the like" may be deemed to include any article having broad faces, such as those mentioned above.

In vitreous enameling table tops and the like, it is preferable that all portions of each table top be uniformly heated in order that warpage and buckling of the article be prevented and in order that the enameled surface may be of high quality. It is further desirable that the heating accorded to each table top be of substantially the same kind and degree in order that the product may be uniform. In addition, dust or other particles should be precluded from attaching to the enameled surfaces and thereby marring said surfaces, spoiling the gloss of the enamel and causing blemishes therein. During the heating, the table tops and the like should be supported by a relatively small supporting means so that the heat may readily reach all portions of the table top and so that said supporting means may not appreciably mar the enameled surface.

It has been the usual practice to vitrify the enamel on table tops and similar articles in ordinary muffle furnaces provided with large doors whereby substantially the entire interior of the muffle may be exposed. The table tops have usually been horizontally disposed adjacent to the bottom of such muffles on a plurality of metal pins or similar devices, the furnace door closed and the table tops heated to a temperature sufficient to vitrify the enamel thereon. After the completion of the vitrifying process, the door of the furnace has been opened, the entire batch removed as by suitable forks and another batch placed in the furnace, and the process repeated.

Under the above mentioned conditions of heating the upper broad surfaces of the table tops have been heated to a greater degree than the lower surfaces. In other words, the table tops have been non-uniformly heated, whereby warpage was of frequent

occurrence, thus reducing greatly the utility of the article. Furthermore, particularly during the period when the furnace door has been opened, dust and other fine particles have settled on the surface of the horizontally disposed articles, thereby reducing the gloss and frequently causing gross imperfections in the enameled surface. Blemishes in the enameled surface have been frequently caused by the pins on which the table tops have been supported. Considerable heat loss also results during the period when the furnace door is opened and table tops and the like are being removed from or introduced into the furnace. Additional heat losses are introduced as a result of the cooling off of the article supports when the furnace door is opened and the absorption of heat by such supports when the door is again closed. It will also be noted that the above mentioned method is discontinuous and partly for this reason has proved unsatisfactory from the standpoint of quantity production.

An object of my invention is to provide a method of vitreous enameling table tops and the like in which the broad faces of such articles are uniformly heated during the vitrifying operation to provide a smooth, uniform enameled surface.

Another object of this invention is to provide a method of vitrifying the enamel on objects having broad surfaces, whereby warpage of such surfaces is prevented.

A further object of the invention is to provide a method of supporting table tops and similar articles in a vitrifying furnace whereby marks or blemishes due to supporting means are minimized.

Another object of the invention is to provide a continuous process of vitreous enameling table tops whereby a large production may be secured and a high quality of product obtained.

Other objects of the invention will be apparent to those skilled in the art from the description of it hereinafter given.

In the drawings:

Figure 1 is a top plan view of a suitable furnace in which my improved process may be carried out;

Fig. 2 is a sectional view on line 2-2 of Fig. 1 showing articles having broad faces,

such as table tops, suitably supported within the vitrifying chamber;

Fig. 3 is an elevation, partly in section, on line 3—3 of Fig. 1;

5 Fig. 4 is a horizontal section on line 4—4 of Fig. 2; and

Fig. 5 is a horizontal section on line 5—5 of Fig. 2.

10 My invention contemplates the heating of enameled table tops and the like to a temperature sufficient to vitrify the enamel thereon by disposing said table tops intermediate substantially parallel uniformly heated heat radiating surfaces. The table tops are preferably supported between said surfaces by relatively small supporting means so that the heat may readily reach all portions of the table top and so that any blemishes from supporting means may be 15 reduced to a minimum. The broad faces of the table top are preferably disposed facing the parallel and relatively adjacent heat radiating portions whereby high heat efficiency is obtained and whereby both faces 20 of the table top are heated substantially uniformly. Thus buckling and warping are substantially prevented and the finished article is given a smooth, flat surface.

30 To meet the needs of large production, said table tops may be conveyed edgewise between substantially parallel and adjacent heat radiating portions whereby each table top will be subjected to uniform heating and the resulting product will be uniform and of 35 high quality. In such continuous process, the heat radiating portions are made of sufficient extent and the rate of conveying said articles is made such that the enamel will be completely vitrified when the table top has 40 completed its passage between said heat radiating portions. The heat radiating portions between which the table top may be conveyed may, of course, be of any suitable shape, such as straight, curved or annular, 45 and said portions may extend and the articles may be conveyed vertically, horizontally or in any intermediate direction.

50 My invention may be carried out in a suitable furnace such as illustrated in the drawings, in which the furnace proper 1 is disposed in cooperative relation to a conveyor mechanism 2 by means of which mechanism articles having broad faces, such as the table tops 3, may be conveyed through the furnace

55 1. The furnace 1, which is shown as being of annular sector shape, is provided with side walls 4 and 5, bottom 6, top portions 7 and 8, and stacks shown generally at 9, all of which members are preferably of brick, 60 those portions which are exposed to high temperatures being preferably of fire brick. Those of said portions which are exposed only to relatively low temperatures may be of ordinary brick.

65 Cooperating with the overhanging top

portions 7 and 8 and spaced from the side walls 4 and 5 and from the bottom 6 are the refractory side walls 10 and 11 and bottom 12, respectively, of the muffle chamber 13, in which articles 3 are heated and enamel 70 thereon vitrified. The top of the chamber 13 is formed in part by fire brick portions of the spaced members 7 and 8, the central portion of said top being sealed by portions of the conveying mechanism 2, as will be 75 more fully described hereinafter.

Further interior structural features of the furnace 1 can well be described in connection with the passage of the hot flue gases there-through, by means of which gases the chamber 13 is heated. Thus, referring particularly to Fig. 4, the fuel for supplying heat to the furnace 1 may be gas or oil entering the symmetrically disposed combustion chambers 14 through the burners 15. The 80 sides of each combustion chamber 14 are provided with apertures 16 and 17 whereby the hot gases may pass into the flue gas chambers 18 or 19.

The flue gas chambers 19 are disposed directly adjacent the chamber wall 11. Above each chamber 19 is disposed a horizontal baffle plate 20. In each combustion chamber, flue gases passing through apertures 17, therefore, pass through a chamber 19, 90 around the horizontal baffle plate 20, through the narrow passageway 21, into the upper flue chamber 22, whence the gases pass through duct 23, and into a stack 24 and upwardly and outwardly thereof. 100

The gases from each combustion chamber passing through apertures 16 enter a flue gas chamber 18, which chamber is of substantially the same height as the chamber 13, and is disposed directly adjacent the vitrifying chamber wall 10. Forming one wall of the chamber 18 is a vertical baffle 26. Flue gases entering a chamber 18, therefore, pass upwardly therethrough over the upper edge of the baffle 26, downwardly through the chamber 28, through the substantially horizontal ducts 29 disposed beneath the floor 12 of the vitrifying chamber 13, into a stack 30, and upwardly and outwardly thereof. 110

By means of the horizontal baffles 20 and the vertical baffles 26 the hot flue gases are forced to pass adjacent to practically the entire adjacent area of the walls 10 and 11 of the chamber 13, thereby securing efficient heating of the walls thereof. It will be noted that the flue gas passages or chambers 18, 19, 21, 22 and 28 are of relatively small transverse dimension, as are also the side walls 10 and 11 and the bottom 12 of the chamber 13. As a result, therefore, the heat of the flue gases is readily transmitted through the bottom 12 and the side walls 10 and 11 to heat the vitrifying chamber 13 and articles 3 disposed therein. 120 125 130

Referring to Fig. 4, it will be noted that each of the burners 15 may be suitably adjusted to assist in the regulation of the temperature of the furnace. Additional control of furnace temperature may be obtained by the provision of suitable dampers within the stacks 24 and 30.

Dividing the lower portion of the furnace into two segments is an aperture 31 which, as shown, is substantially of the same height as the combustion chambers 14. The aperture 31 provides room for portions of the conveying mechanism 2 and also for burners 15. The endless conveyor mechanism 2, by means of which articles 3 may be disposed within and removed from the chamber 13, is shown as comprising a vertical rotatable shaft 32 supported by an end thrust bearing 33 and by the structural members 34 and bearing 35. At the upper end of the shaft 32 is mounted a wheel-like structure comprising a hub 36, spokes 37 and rim 38. From the rim 38 are suspended article supporting means 39, which extend into the chamber 13 through aperture 40. Heat is prevented from escaping from the chamber 13 through the aperture 40 by a suitable closure 41, provided with the substantially vertical members 42. The horizontal portion of the closure 41 is preferably of refractory material and the vertical runners 42 may be of metal or of refractory material. The vertical portions 42 move in sand 43 disposed in the concentric grooves 44 and 45. The grooves 44 and 45 are completely circular, the portions between the ends of the furnace being bridged by channel members 46 and 47. The motive power for the conveyor mechanism 2 may be provided by a motor 48 disposed outside of the furnace and operatively connected to the shaft 49, which extends through the aperture 31. The shaft 49 drives the shaft 32 through the bevel gears 50 and 51. As shown, the power transmitting portions of the conveyor mechanism 2 are well protected and insulated from the heat of the furnace.

The supports 39 and the articles 3 supported thereby enter and leave the furnace through relatively small apertures 52, which may be partially or entirely closed by doors 53, which are shown as sectionally operable. The effective size of the apertures 52 may thus be made as small as is permissible by the size of the articles 3, thereby minimizing heat losses through said apertures.

With apparatus such as herein described, my improved process may be carried out as follows: An article having broad faces, such as a table top 3, is caused to be supported, preferably outside the furnace, by a supporting or suspending means 39, the table top being preferably so supported as to travel edgewise with its broad faces sub-

stantially parallel to the direction of movement. Suspending means 39 is of relatively small mass so that but a small amount of heat will be absorbed thereby and so that substantially all portions of the table top 3 may receive heat directly from the walls 70 of the chamber 13. The suspending means 39 is shown as engaging the table top 3 under a flanged edge thereof. Thus, marks or blemishes left by supporting means are substantially eliminated, the contacting surface between the support 39 and article 3 being preferably made as small as possible.

By rotation of the conveying means 2, the article 3 is moved edgewise through one of the narrow apertures 52 into the vitrifying chamber 13 and is conveyed through said chamber 13, the broad faces of the article 3 being disposed during said conveyance relatively adjacent the walls of the chamber 13 and being uniformly subjected to heat from said walls. In a substantially closed chamber, such as shown, the temperature to which the article 3 is exposed may be very readily controlled and, in addition, dust or other small particles may not readily come in contact with the surfaces to be enameled to dull or mar said surfaces. The temperature of the chamber 13 is so regulated and the speed of movement of the conveying mechanism is such that the enameled surface of an article 3 is completely vitrified when said article or table top is removed from the chamber 13 through the other aperture 52. During the passage of a table top or the like through the chamber 13, all of the surfaces thereof are uniformly subjected to the vitrifying heat, whereby the vitrified enamel surface produced is of very high uniform quality and whereby any warpage of the table top is substantially eliminated.

The furnace 1 and conveying mechanism 2, as shown, are adapted for the continuous enameling of articles 3. Thus, when the conveyor 2 is in motion, table tops or the like, whose enamel coated surfaces are to be vitrified, may be continuously attached to supporting means 39 and finished articles may be continuously removed therefrom. With such a continuous process, every article or table top 3 is subjected to the same degree and amount of heat, whereby uniformity of product is assured.

The dimension of the chamber 13 between the side walls 10 and 11 thereof is preferably as small as possible, thereby decreasing the size of the furnace, increasing the economy of operation, and providing for the ready transfer of heat from the walls of the chamber to the broad faces of the articles to be heated.

The heating chamber 13 may extend in a vertical or other direction rather than horizontally, as shown in the drawings. In such

case, the table tops or similar articles 3 may be conveyed lengthwise of said chamber in a vertical or other direction.

It will thus be seen that I have provided a method of vitreous enameling articles having broad faces, whereby warpage or other distortion of said articles is substantially eliminated and whereby an enameled surface of high quality is produced.

It will also be noted that I have provided a continuous process of vitreous enameling articles having broad faces, whereby a large production of a uniform product of high quality may be efficiently produced.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

25. What I claim is:

1. The process of vitrifying enamel on a substantially flat article having broad faces, which comprises supporting said article substantially vertically, and subjecting the opposite faces of the article substantially uniformly to radiant heat to thereby substantially uniformly heat said article and vitrify the enamel thereon.

2. The process of vitrifying enamel on a plurality of substantially flat articles having broad faces, which comprises supporting said articles with the flat faces thereof substantially in vertical position, and subjecting said opposite faces of the articles to radiant heat to thereby substantially uniformly heat the faces of the articles and vitrify the enamel applied to said articles without appreciable buckling and warpage of the articles.

3. The process of vitrifying enamel on a plurality of articles having substantially flat, broad surfaces, which comprises supporting the articles with the flat surfaces thereof substantially in vertical position and subjecting the faces of the articles to radiant heat without materially obstructing the radiation of heat to the said faces by the supporting means, thereby heating said articles substantially uniformly and vitrifying the enamel thereon.

4. The process of vitrifying enamel on a series of substantially flat articles having

broad faces, which comprises supporting said articles substantially vertically, exposing said articles to sources of heat and subjecting the opposite faces of the articles to said sources of heat without obstructing the transmission of heat to said faces of the articles, thereby heating them uniformly and vitrifying said enamel, and conveying the articles away from the sources of heat.

5. The process of vitrifying enamel on a series of flat metallic articles having broad faces, which comprises supporting said articles substantially vertically, continuously conveying said series of articles between sources of radiant heat and subjecting the opposite faces of the articles to substantially the same amount of heat and thereby uniformly heating them and vitrifying the enamel.

6. The process of vitrifying enamel on a series of substantially flat metallic articles having substantially broad faces, which comprises suspending said articles by their upper marginal portions, continuously conveying said articles consecutively between sources of heat without obstructing the transmission of heat to the faces of the articles and thereby heating substantially all portions of the articles uniformly and vitrifying the enamel, and continuously conveying the articles away from the sources of heat.

7. The process of vitrifying enamel on a series of substantially flat metallic articles having broad faces, which comprises suspending said articles substantially vertically with hook suspending means, continuously conveying said articles between sources of heat and heating the faces of the articles substantially uniformly to vitrify the enamel and thereby substantially prevent buckling and warping of the articles and continuously conveying said articles away from the heat after vitrification of the enamel.

8. The process of vitrifying enamel on a plurality of articles having substantially flat broad surfaces, which comprises supporting each of the articles with the flat broad faces thereof in substantially vertical position, and subjecting the articles substantially uniformly to radiant heat without materially obstructing the radiation of the heat to the articles by the supporting means, to vitrify the enamel and thereby substantially prevent buckling and warping of the articles.

In testimony whereof I affix my signature.
EDGAR H. WEIL.
